CLAIM

The ornamental design for a handle for surgical tool, as shown and described.

DESCRIPTION

FIG. 1 is a front isometric view of a handle for surgical tool in accordance with the new design;

FIG. 2 is a front view thereof;

FIG. 3 is a rear view thereof;

FIG. 4 is a left side elevation view thereof;

FIG. 5 is a front view thereof; and,

FIG. 6 is a rear view thereof.

The broken lines shown in FIGS. 1-6 are directed to environment only; the broken lines form no part of the claimed design.
